DELBERT O. TRAEGER, OF PORTERVILLE, CALIFORNIA, ASSIGNOR OF ONE-HALF TO
WALTER J. GODLEY, OF PORTERVILLE, CALIFORNIA.

SPOOL-HOLDER.

1,260,597.

Specification of Letters Patent. Patented Mar. 26, 1918.

Application filed April 18, 1917. Serial No. 163,002.

To all whom it may concern:

Be it known that I, DELBERT O. TRAEGER, a citizen of the United States, residing at Porterville, in the county of Tulare and 5 State of California, have invented certain new and useful Improvements in Spool-Holders, of which the following is a specification.

This invention relates to spool holders, 10 and has for its primary object to provide a simple and inexpensive holder for spools which may be quickly and easily applied to and detached from a suitable support. A further object of the invention is to provide 15 a spool holder of this character to which a spool may be quickly and easily applied or detached, and which will rotatably support the spool, and hold the same against falling upon the floor or entangling the thread 20 wound thereon.

Still further objects reside in providing a device of this character which may be constructed at exceedingly low cost, and of 25 which the most important parts may be stamped from sheet metal; which is constructed in such manner as to enable the movable parts to be easily grasped and operated to facilitate the ready attachment or detachment of the holder from its support; which is constructed in such manner 30 as to be incapable of scratching or scarring the support to which it is applied; and which will prove thoroughly efficient in use.

With these objects in view, together with 35 others which will appear as the description proceeds, the invention resides in the novel formation, combination, and arrangement of parts, all as will be described more fully hereinafter, illustrated in the drawings, and 40 particularly pointed out in the claims.

In the drawings:—

Figure 1 is a side elevation of a spool holder constructed in accordance with the invention; the view illustrating the holder 45 in use,

Fig. 2 is a top plan view of the holder,

Fig. 3 is a longitudinal sectional view taken through the improved holder, and

Fig. 4 is a transverse sectional view taken 50 on line 4—4 of Fig. 3.

The invention in its preferred embodiment comprises a pair of leaves 5 and 6 respectively, which are capable of moving toward and away from each other. These

leaves are hingedly connected together as 55 at 7, and form a clamp. The leaf 5 which will be hereafter referred to as the upper leaf, is provided with an upstanding spindle or post 8, which rotatably supports a spool. Means is provided for normally forcing the 60 leaves 5 and 6 together, so that when the said leaves are engaged with the upper and lower surfaces respectively of a table, board, window sill, or the like, the holder in its entirety will be held firmly in position thereon. 65

The upper leaf 5 is formed of relatively thin sheet metal, such as aluminum, and is of substantially circular formation. Projecting outwardly from one edge of this leaf is a relatively narrow extension 9, the outer 70 extremity of which is adapted to be bent downwardly as at 10 to form a thumb engaging portion. This extension is also provided upon its opposite sides with downwardly projecting arms 11, the said arms 75 being equipped with registering apertures.

The bottom leaf 6 is constructed preferably of the same material as the upper leaf, and may, if desired, have its bottom portion of restricted diameter. This bottom leaf is also provided with an extension indicated at 12, from the lateral edges of which upwardly extending arms 13 project. The arms 13 are equipped with registering apertures, equal to the diameter of the apertures in the arms 11, and the apertures of the arms upon the upper and lower leaves are adapted to register to accommodate the hinge pin 7. It will be observed that the thumb portion 10 extends downwardly a 90 distance sufficient to entirely close the end portion of the lower extension 12, so that danger of the thread or cord upon the spool becoming engaged with the extremities of said extension is obviated. 95

To normally maintain the leaves 5 and 6 in engaged or clamping position, a spring 14 is employed. This spring encircles the hinge pin 7 between the interfitting arms, and the extremities of the spring bear respectively against the upper and lower extensions 9 and 12. 100

The body portion of the leaf 6 is provided with a downwardly extending member 15, to form a gripping portion for the fore finger 105 of the hand when attaching or detaching the device to a support. The member 15 is, in the present instance, formed by angularly

cutting away the central portion of the leaf 16, and bending downwardly that portion of the metal defined by the incisions.

The portions 10 and 15 are so located upon 5 the completed holder as to be conveniently engaged by the thumb and fore finger respectively of the hand, and when thus gripped, pressure applied inwardly to the member 10 by the thumb will cause the 10 upper leaf 5 to rock upwardly upon the pivot 7 to disengage the holder from its support. When it is desired to apply the holder to a support, pressure is applied to the thumb piece 10 so as to open the clamping 15 members or leaves sufficiently to enable the same to clamp over the support. Upon releasing the thumb piece 10, the spring 14 forces the leaves 5 and 6 into firm engagement with the support.

20 It will be observed that the central portion of the leaf 5 is bowed upwardly. By so forming the upper leaf, the retaining head or nut for the post 8 is accommodated by the concave under face of the plate or 25 leaf so as to be held out of engagement with the support. This particular construction prevents the retaining head of the post from scratching or scarring the support upon which the holder is to be used. A further function of the rounded plate 5 is to 30 reduce the friction between the lower end of the spool and the leaf. The rounded portion engages the spool only at the juncture of the post 8 with the leaf 5, and the 35 spool supported by the post is capable of freely rotating.

It is preferred that the inner faces of the leaves 5 and 6 be so finished or polished as not to present rough surfaces to scratch

or scar articles of furniture to which the 40 holder is applied, and it is preferred that the leaves of the holder be formed of aluminum. Should it be desired, the gripping faces of the leaves may be lined with padding, such as felt or the like.

45 While the present disclosure is that of what I believe to be the preferred embodiment of the invention, it is to be understood that the invention is not limited thereto, but that various changes may be made in 50 the construction, arrangement, and proportion of parts, without departing from the spirit of the invention, as defined in the appended claims.

55 What is claimed is:—

1. In a device of the class described, a holder comprising a pair of leaves, interfitting arms at adjacent edges of said leaves, a hinge pin connecting said arms, means for rocking said leaves toward each other, a 60 thumb piece formed adjacent the arms of one of said leaves and extending below the lowermost extremity of the arms of the opposite leaf, a finger piece on said opposite leaf, and means for supporting a spool on 65 one of said leaves.

2. In a spool holder, a pair of leaves, one of said leaves being concaved, a post secured to said leaf and extending upwardly from the center of said concave portion, and finger pieces formed integral with said leaves.

70 In testimony whereof I affix my signature in presence of two witnesses.

DELBERT O. TRAEGER.
